Nathan K. Morris, 4th and Railroad Aves.,
Neptune City, N.J.

Filed Feb. 20, 1961, Ser. No. 64,005

Term of patent 7 years

(Cl. D2—3)

FIGURE 1 is a side elevational view of a combined measuring and dispensing cap for a bottle or the like, showing my new design, the opposite side being a mirror image of the side shown; and

I claim:

The ornamental design for a combined measuring and dispensing cap for a bottle or the like, as shown and described.
